UNITED STATES PATENT OFFICE.

GEORGE S. GALLAGHER, OF NEW YORK, N. Y., ASSIGNOR TO ZILLIAH B. GALLAGHER, EMMA G. GALLAGHER, AND HARRY F. GALLAGHER, OF SAME PLACE.

SMOKE-CONSUMING DEVICE FOR FURNACES.

SPECIFICATION forming part of Letters Patent No. 655,221, dated August 7, 1900.

Application filed October 25, 1899. Serial No. 734,696. (No model.)

To all whom it may concern:

Be it known that I, GEORGE S. GALLAGHER, a citizen of the United States, residing at New York city, in the county and State of New York, have invented an Improvement in Smoke-Consuming Devices for Furnaces, of which the following is a specification.

This invention relates to devices for consuming smoke in furnaces, the object being to prevent the same leaving the fire-chamber and to effect the consumption of the same before the products of combustion pass over the bridge-wall of the furnace and to the chimney. In carrying out my invention I effect this condition by drawing the smoke off the fire through flues and injecting the same commingled with air in currents of force above the fire, where the commingled smoke and air are fully consumed because of the presence of abundance of air. The smoke is consumed in the upper portion of the fire-chamber before the products of combustion pass over the bridge-wall, and the effective heat units are thus greatly increased. In order to accomplish this result, I construct the bridge-wall of the furnace with especially-arranged flues for the smoke and for air, all of which are hereinafter more particularly described, it being borne in mind that the air-currents of force or the draft are produced through the arrangement of flues by the action of a tall chimney.

In the drawings, Figure 1 is a partial longitudinal section and elevation; and Fig. 2, a cross-section at $\alpha\alpha$ of Fig. 1, representing my improvements. Fig. 3 is a partial longitudinal section upon the line yy of Fig. 2, and Fig. 4 is a partial longitudinal elevation and section representing a modification. The boiler a , the metal front b , the combustion-chamber c , the grate-bar d , the ash-pit e , the foundation f , and the side supporting-walls $g\ g'$, as well as the smoke-pipe h , are of usual construction in furnaces and do not require further description.

The bridge-wall i occupies about the usual position, and I provide entrance-flues $2\ 3$ for air from opposite sides of the furnace through the side walls $g\ g'$ and across through the

bridge-wall i , there being, preferably, a central division closing one flue from the other. Connected to these flues $2\ 3$ are branch flues $5\ 6$, extending through the side walls of the furnace and opening into the ash-pit e beneath the grate-bars d . Air is thus supplied beneath the grate-bar for the combustion of the fuel.

In the bridge-wall i there are a series of double air-return flues $7\ 8$, placed horizontal and spaced apart with end connections between the horizontal portions of said flues. I provide air-flues 9 , parallel with the upper portions or members 7 of the double flues, the rear ends of which open into the flues $2\ 3$ and the forward ends of which flues join with the forward ends of the flues 7 , there being between the flues 7 and 9 a narrow division running toward the front of the bridge-wall and terminating a short distance before reaching the front, as will be seen by the section Fig. 3. The construction and operation of this part are similar to an injector.

The chimney employed for creating a draft in a furnace in the usual manner draws the air in currents of force into the flues $2\ 3$, through the flues 9 , and out into the combustion-chamber c . A suction action is thus produced, which draws the smoke from over the fire beneath the discharge-level of the air into the flues 8 and through the rear connection therewith into the flues 7 , and the smoke commingled with the air at the exit-opening of the flues 7 and 9 is forced out into the combustion-chamber c , where, in the presence of an abundant supply of air, the smoke is consumed under the boiler above the fire in the combustion-chamber and the effective heat units are increased, so that the products of combustion that pass over the bridge-wall and through the flues of the boiler and away by the chimney in the usual manner are clear gaseous products of combustion free of smoke. Fig. 2 shows by the arrows the air passing from the flues $2\ 3$ along and down the branch flues $5\ 6$ and out into the ash-pit e beneath the grate-bars. It will thus be seen that air is provided not only for the combustion of the fuel, but for drawing the smoke off the sur-

face of the fire, commingling it with air and burning the same above the fire.

In the modification, Fig. 4, I have shown a hollow arch *k*, extending across between the side walls *g g'* through the combustion-chamber, the under surface of which arch is perforated with air-openings 10. The hollow arch is connected with air-openings through the side walls for the additional supply of air, the object being to provide an abundant supply of air to insure perfect combustion beneath the boiler.

I claim as my invention—

1. The combination in a furnace with the grate-bars and a bridge-wall, of flues for the draft or currents of air under force, extending longitudinally through the bridge-wall, and short flues transversely in the bridge-wall, and connecting therewith, and acting to draw the smoke off the surface of the fire and commingle the same with the said currents of air, and eject the same into the combustion-chamber over the fire to be consumed, substantially in the manner and for the purposes set forth.

2. The combination in a furnace with the grate-bar and the bridge-wall, of entrance-flues for the draft or currents of air under force, a series of double or return flues connected and placed horizontally in said bridge-wall, flues for the draft acting in conjunction with the said series of return-flues as ejectors, whereby the smoke is drawn off the fire through the said series of double flues and commingled with the currents of air is forced over the fire into the combustion-chamber to be consumed, substantially in the manner and for the purposes set forth.

3. In a furnace, the combination with the

grate-bar and the bridge-wall, of entrance-flues 40 23 from opposite sides through the said bridge-wall, a series of parallel double or return flues 7 8 connected at their inner ends, air-flues 9 parallel with the flues 7 and connecting at one end with the entrance-flues 2 3 and at the other end forming a common exit-opening with the flues 7, substantially as and for the purposes set forth.

4. In a furnace, the combination with the grate-bar and the bridge-wall, of entrance-flues 50 23 from opposite sides through the said bridge-wall, a series of parallel double or return flues 7 8 connected at their inner ends, air-flues 9 parallel with the flues 7 and connecting at one end with the entrance-flues 2 3 55 and at the other end forming a common exit-opening with the flues 7, and the branch flues 5 6 through the side walls of the furnace and opening beneath the grate-bars, substantially as and for the purposes set forth.

5. In a furnace, the combination with the grate-bar and the bridge-wall, of entrance-flues 60 23 from opposite sides through the said bridge-wall, a series of parallel double or return flues 7 8 connected at their inner ends, air-flues 9 parallel with the flues 7 and connecting at one end with the entrance-flues 2 3 65 and at the other end forming a common exit-opening with the flues 7, and a hollow arch *k* having air-openings 10 extending across the combustion-chamber forward of the bridge-wall, substantially as set forth.

Signed by me this 20th day of October, 1899.

GEORGE S. GALLAGHER.
